United States Patent Office

Des. 197,765
Patented Mar. 24, 1964

197,765

TOWER

Chancy M. Lott, 5834 Keokuk Ave., Woodland Hills,
Calif., and Christopher G. Taylor, 9612 Haskell,
Sepulveda, Calif.

Filed Dec. 3, 1962, Ser. No. 72,695

Term of patent 14 years

(Cl. D13—1)

FIG. 1.

FIG. 2.

FIG. 3.

FIG. 1 is a front elevational view of the design for a tower;

FIG. 2 is an enlarged, fragmentary front elevational view; and

FIG. 3 is an enlarged top plan view thereof with the hexagonally shaped base fragmentarily shown for convenience of illustration only.

We claim:

The ornamental design for a tower, as shown and described.
